UNITED STATES PATENT OFFICE.

WARREN C. SCHILLING, OF GREEN BAY, WISCONSIN, ASSIGNOR TO THE PAPER NOVELTY COMPANY, OF GREEN BAY, WISCONSIN.

DESIGN FOR A PAPER CARTON.

Application filed June 9, 1926. Serial No. 17,995. Term of patent $3\frac{1}{2}$ years.

To all whom it may concern:

Be it known that I, WARREN C. SCHILLING, a citizen of the United States, residing at Green Bay, in the county of Brown and State of Wisconsin, have invented a new, original, and ornamental Design for Paper Cartons, of which the following is a specification, reference being had to the accompanying drawing, forming part thereof.

The figure is a perspective view of a carton made up in accordance with the present invention.

I claim:

The ornamental design for a paper carton, as shown.

WARREN C. SCHILLING.
